UNITED STATES PATENT OFFICE.

HENRY J. DONNELLY, OF SOUTH BELLINGHAM, WASHINGTON.

DEVICE FOR CLEANING WATER COCKS.

Application filed December 16, 1924. Serial No. 756,280.

To all whom it may concern:

Be it known that I, HENRY J. DONNELLY, a citizen of the United States, residing at South Bellingham, in the county of Whatcom and State of Washington, have invented certain new and useful Improvements in Devices for Cleaning Water Cocks, of which the following is a specification.

This invention is a device for removing incrustation from water valves. It is customary at the junction of a water main with a service pipe to provide a cut-off valve which is normally open but which may be easily closed when repairs to the service pipe are necessary or, for any other reason, it is desired to cut off the flow of water into the service pipe. Corrosion occurs in these cut-off valves, especially at the points where they are fitted into the main, and the accumulated incrustation which results from the corrosion eventually reduces the flow in the service pipe to such an extent that it is negligible. It is the object of my invention to provide a very simple tool by the use of which this deposit or accumulation may be easily removed without requiring the valve to be separated from the main and without reducing the pressure in the main while, at the same time, without exposing the operator to wetting, as frequently occurs by the methods now in use. The invention is illustrated in the accompanying drawing and consists in certain novel features which will be particularly pointed out in the appended claim.

In the drawing:

Figure 1 is an elevation of my tool in operative position;

Fig. 2 is a longitudinal section of a valve having the tool applied thereto, the barrel or guiding body of the tool being also shown in section;

Fig. 3 is an enlarged detail view, partly in section, showing one manner of mounting the head or striker block upon the plunger or push rod;

Fig. 4 is a detail perspective view showing another manner of mounting the head upon the rod, and

Fig. 5 is a detail perspective view showing a different form of head from that shown in the other figures.

In the drawing, the reference numeral 1 indicates a portion of a water main, in the wall of which is fitted a cut-off valve 2 of

ordinary turning plug type. This valve, as clearly shown, is threaded at one end into the main and at its opposite end is externally threaded so that it may be connected with the service pipe. The bore of the valve casing at the delivery end thereof is also internally threaded, as clearly shown in Fig. 2.

My tool comprises a barrel 3 which has a smooth bore extending entirely through the same and is externally threaded at its opposite ends, as shown at 4, whereby either end may be engaged with the internally threaded bore of the valve casing. Between its ends, this barrel is provided with an annular rib 5 which is preferably formed with flat faces so that it may be easily engaged by a wrench or other turning tool if necessary. Adjacent each end of the barrel is a disk or annular flange 6, and immediately adjacent the outer face of each flange or disk is a short smooth surface 7 to accommodate a gasket 8 which is placed around the barrel and against the annular flange or disk so that, when the barrel is engaged in the end of the valve casing, a leak-proof joint will be produced. Slidably fitted through the bore of the valve is a push rod 9 which is equipped at each of its ends with a head or striker disk 10 which is adapted to engage in and work through the port of the valve turning-plug as well as through the bore of the valve casing. In Fig. 2, the head is shown engaged in the port of the valve turning-plug.

The head or striker may be secured to the push rod in any convenient or preferred manner. In Fig. 3, I have shown the end of the rod reduced, as at 11, and the head 10, in this arrangement, has a smooth bore, the extremity of the rod being upset against the outer face of the head, as indicated at 12, after the head has been fitted over the reduced portion of the rod and against the annular shoulder 13 provided at the base of said reduced portion. In Fig. 4, the end of the rod is shown as provided with threads 14 and the bore of the head is threaded, as at 15, so that it may be easily fitted to and secured upon the end of the rod. In Figs. 1 to 4, the head is circular in form so that it is adapted to operate in a turning plug having a circular port, while in Fig. 5 the head 16 is elongated so that it may be oblong or ellipsoidal to engage in and pass through an elliptical port.

The invention contemplates the provision of a plurality of barrels and push rods, each push rod carrying a head at each end thereof and the heads being of different diameters. The heads may also be interchangeable and the diameters and outlines of the heads will be such that the workman may at once dispose the proper head in position to engage the port of the valve which is to be cleaned. In use, the valve is first closed by rotating the turning plug in the usual manner. The service pipe is then disconnected from the valve casing and the barrel 3 engaged in the valve casing so that leakage will be prevented by the gasket 8 and a head 10 of the proper size and form to fit closely within the port of the turning plug will be presented to the plug. The valve is then opened and the push rod 9 forced downwardly through the valve turning-plug and the end of the valve casing thereby breaking off the accumulated deposit and scraping the same from the bore of the valve casing so that the valve will be cleaned and the entire capacity of its bore will be again available for the passage of water. The push rod is then lifted so that the working head 10 thereon will be withdrawn from the port of the turning plug. The valve is then closed, the barrel 3 rotated so as to be removed from the valve casing, the service pipe then again connected to the valve, and the valve opened so that the service pipe will then be in condition for use.

It will be understood that each tool is adapted without any change to be applied to a valve having either of two standard dimensions. For example, the push rod may be equipped at one end with a head having

a diameter of one-half inch and at the opposite end with a head having a diameter of five-eighths of an inch. Accordingly, the operator will apply the barrel to the valve so that one or the other head will be presented thereto accordingly as the port of the turning plug and the bore of the valve casing has a diameter of one-half of five-eighths of an inch. The device is exceedingly simple and may be easily applied to or removed from any valve which is to be cleaned. The deposit in the valve may be very quickly removed by a few blows administered thereupon through reciprocation of the push rod and no reduction of pressure in the water main will be required to permit the device to be operated.

Having thus described the invention, I claim:

A tool for cleaning turning plug valves comprising a barrel having a smooth straight bore extending longitudinally therethrough, the barrel being constructed at its ends to engage within the delivery end of a valve casing, an annular flange on the barrel adjacent each end of the same, gaskets carried by the barrel and seated against the respective flanges to engage the end of the valve casing and prevent leakage, a rigid rod slidably and snugly fitted through the bore of the barrel, and a head carried by each end of the rod, the head being of greater diameter than the rod whereby to prevent withdrawal of the rod from the barrel and of a form to fit closely in the port through the turning plug of the valve.

In testimony whereof I affix my signature.

HENRY J. DONNELLY. [L. S.]
